Primary Examiner — John Windmuller*Assistant Examiner* — Steven Czyz*(74) Attorney, Agent, or Firm* — Adam K. Sacharoff;
 Much Shelist, P.C.(57) **CLAIM**

The ornamental design for a garment rack, as shown and described.

DESCRIPTION

FIG. 1 is a front perspective view of a garment rack, showing our new design;

FIG. 2 is a front perspective view thereof, illustrated in a full extension position;

FIG. 3 is a front perspective view thereof, illustrated in a partial extension position;

FIG. 4 is a front elevation view thereof;

FIG. 5 is a back elevation view thereof;

FIG. 6 is a left side view thereof;

FIG. 7 is a right side view thereof;

FIG. 8 is a top plan view thereof; and,

FIG. 9 is a bottom plan view thereof.

1 Claim, 7 Drawing Sheets---
